UNITED STATES PATENT OFFICE.

HENRY CUTLER, OF NORTH WILBRAHAM, MASSACHUSETTS, ASSIGNOR TO
HENRY WILLIS CUTLER, OF SAME PLACE.

AUTOMATIC GRAIN-WEIGHING SCALE.

SPECIFICATION forming part of Letters Patent No. 375,267, dated December 20, 1887.

Application filed March 12, 1887. Serial No. 230,610. (No model.)

To all whom it may concern:

Be it known that I, HENRY CUTLER, of North Wilbraham, in the county of Hampden and State of Massachusetts, have invented a new and Improved Automatic Weighing Scale, 5 of which the following is a full, clear, and exact description.

The object of my invention is to provide a new and improved scale for weighing grain, 10 which is simple and durable in construction and automatic in operation.

The invention consists in various parts and details and combinations of the same, as will be fully described hereinafter, and then pointed 15 out in the claims.

Reference is to be had to the accompanying drawings, forming a part of this specification, in which similar letters of reference indicate corresponding parts in all the figures.

20 Figure 1 is a side elevation of my improvement with parts in section. Fig. 2 is an end elevation of parts of the same with parts in section. Fig. 3 is an enlarged end elevation of the lower part of the oscillating lever and 25 its bearing with parts in section. Fig. 4 is an end elevation of the drop-bottom of the grain-receptacle. Fig. 5 is a sectional side elevation of the oscillating lever on the lines $y-y$ of Fig. 3. Fig. 6 is a similar view of the 30 same on the lines $z-z$ of Fig. 3; and Fig. 7 is an enlarged end view of the lower end of the oscillating lever with its bearing in section.

My improved weighing-scale A is mounted on a central standard, B, on the upper end of 35 which is secured the bearing C, provided with the offsets C', each having a V-shaped groove, C', in which rests the V-shaped lower end, D', of the oscillating lever D. In the middle of the lower end of the latter is secured to the 40 bearing C a curved plate, C', which bears on the upwardly-turned knife-edge plate D', attached to the lever D. The curved plate C' holds the three knife-edge bearings D', D', and D' in place, and prevents an upward motion 45 of the levers D. The set-screws C', screwing in the bearing C and against the edges of the ends D', prevent a lateral motion of the oscillating lever D, but permit an oscillating movement of the same.

50 Near the upper end of the oscillating lever D is formed the cylinder E, extending cross-

wise at equal distances on both sides of the lever D. In the cylinder E travels a ball, E', and the ends of the said cylinder are adapted to rest alternately on the arms F', with which 55 the said ends of the cylinder E come in contact when the lever D oscillates. The arms F' extend from the bracket F, secured to the central standards, B.

Between the cylinder E and the fulcrum of 60 the oscillating lever D are arranged the arms G, extending equal distances from both sides of the lever D, and on each arm G is pivoted a lever, G', limited in its upward movement by a stop-pin, G'', on the respective arm G. 65 The outer end of each lever G' is loosely connected with the lower end of the S-shaped hook H, hung with its upper end on the knife-edge bearing I', projecting from the inner end of the weighing-beam I, fulcrumed on the arm 70 F', secured to the bracket F. The weighing-beam I is provided with the usual poise, I'', and with the regulating-ball I'', screwing on the rod I', held on the beam I.

The outer end of each weighing-beam I supports a second weighing-beam, J, of standard construction, and on which is hung the grain-box K, provided on each side of its separate cap with a rod, K', passing through an eye, K'', on the box K, and provided on its lower 80 end with a nut, K'', on which rests one end of the spring K', coiled on the said rod K' between the nut K'' and the eye K''. Each box K is also provided with a hinged drop-bottom, L, having a counter-weight, L', on one end 85 and adapted to engage at its other end a catch, N, pivoted on the box K and operated by a tube-lever, O, fulcrumed on the standard B. In the tube-lever O travels a ball, O'. Centrally above the standard B is placed a pivot, 90 P, secured to a suitable beam, P', and on this pivot P oscillates the grain-spout Q, held in an inclined position in relation to the boxes K and provided on its upper end with the receiving-funnel Q'. The lower end, Q'', of the 95 spout Q is adapted to open alternately into the spouts R, secured to a beam, S, and leading to the respective boxes K.

The lower end, Q'', of the grain-spout Q, when traveling from one fixed spout R to the other, 100 is closed by a segmental rim, T, held on the said beam S.

The grain-spout Q is operated from the oscillating lever D, which is connected at its upper end by the rods U with one end of the levers V, respectively pivoted on the beam P' 5 and connected by the link W with the end of the funnel Q' of the spout Q.

The operation is as follows: In the position shown in Fig. 1 the box K to the right of the standard B is to be filled with grain entering the funnel Q' of the spout Q and passing, by means of the stationary spout R, into the box K. As soon as the weight of the grain in the box K corresponds to the weight to which the beams I and J are set, then the inner end of the beam I moves upward and acts by the S-shaped hook H on the lever G', which by its connection with the arm G causes the lever D to tilt to the left, whereby the several moving parts are thrown into the position shown in dotted lines in Fig. 1. The tilting motion of the lever D is stopped when the cylinder E strikes the arm F' on the left side. The spout Q is turned on its pivot by the movement of the lever D, which acts by the rods U on the levers V, and the latter by the links W turn the spout Q. Grain entering the spout Q while the latter oscillates accumulates in the lower end, Q², as the opening of the latter is closed by the rim T. When the box K 30 has received part of its load of grain, then the weight of the grain will compress the springs K', and the box will settle sufficiently to move the right end of the lever-tube O below its fulcrum, so that the ball O', which is in the other end of the tube O, will roll over to the end of the lever near the box K filled with grain.

As soon as the box K is filled, it commences to move downward, operating the weighing-beam I, as above described. Then the catch N comes in contact with the depressed end of the lever-tube o, and is disengaged from the drop-bottom L, which falls downward by the weight of the grain, and the latter is discharged into 45 bags or other receptacles. As soon as the box K is empty, then the bottom L swings back to its former position, caused by the counter-weight L'. As soon as the spout end Q² connects with the stationary spout R on the left of the standard B, then the same operation as above described takes place on the left side of the device. When the weighing takes place on the one side, the S-shaped hook H on the other side hangs free and is disconnected from the respective arm G until the weighing-beam I on the other side moves upward. Thus the latter is not affected in weighing correctly by the double arrangement. When the lever D oscillates and passes a vertical position, then 55 the ball E rolls to the upper side, thus finishing the stroke of the lever D without the assistance of the respective weighing-beam I.

It will be seen that the standard scales J, which are set to a certain weight, indicate any

inaccuracies which may occur, while the upper beam I determines the weight of the load. The inevitable daily change in specific gravity, as well as in the velocity at which the grain runs into the boxes K, will cause some little inaccuracies, which are detected by the beams 65 J and corrected by adjusting the poise on the beam I.

Having thus fully described my invention, I claim as new and desire to secure by Letters Patent—

1. In a weighing-scale, the combination, with an oscillating lever, of weighing-beams loosely connected by S-shaped hooks with the said lever, grain-boxes supported on the said beams, and a pivoted grain-spout adapted to 80 connect alternately with the said grain-boxes and operated from the said oscillating lever, substantially as shown and described.

2. In a weighing-scale, the combination, with an oscillating lever, of stop-plates limiting the movement of the said lever, S-shaped hooks connected with the said lever, weighing-beams supporting the said hooks, and grain-boxes supported on the said weighing-beams, substantially as shown and described.

3. In a weighing-scale, the combination, with an oscillating lever having arms, of a lever-arm pivoted on each of the said arms and having its upward movement limited by a stop under said arm, and an S-shaped hook adapted 95 to engage the said lever-arm, and a weighing-beam supporting the said hook, substantially as shown and described.

4. In a weighing-scale, an oscillating lever having arms, a cylinder mounted on the said lever, a ball held loosely in the said cylinder, and stop-plates for limiting the movement of the said lever, in combination with a lever-arm pivoted to each of the said arms of the oscillating lever, an S-shaped hook adapted 100 to engage the said lever-arm, and a weighing-beam supporting the said hook, substantially as shown and described.

5. In a weighing-scale, the combination, with the weighing-beams, of yielding boxes held on the said beams, a counterweighted drop-bottom hinged on each of the said boxes, and means, as described, for locking and unlocking the said drop-bottoms on the said boxes, substantially as set forth.

6. In a weighing-scale, the combination, with the yielding grain-boxes, of a drop-bottom hinged on each of the said boxes, a spring-catch pivoted on each of the said boxes and adapted to engage the said drop-bottom, a 115 tube-lever adapted to engage the said spring-catches, and a ball traveling in the said tube-lever, substantially as shown and described.

HENRY CUTLER.
